UNITED STATES PATENT OFFICE

WILLIS K. HODGMAN, JR., OF TAUNTON, MASSACHUSETTS

RETARDING CHAMBER

Application filed February 2, 1929. Serial No. 337,102.

This invention relates to a retarding chamber apparatus for a liquid supplying system under pressure. Such a system is exemplified in the well-known automatic fire sprinkler systems. In such systems it is desirable that an alarm be given whenever the liquid under pressure flows continually under full head for a predetermined period, as, for example, within a short predetermined period 5 after a sprinkler has opened. But it is essential also that so far as possible no alarm shall be given with a lesser flow, as, for example, when the flow results from pulsations due to variations in pressure of the supply 10 or from water hammer. It is also desirable that the entire flow diverted to operate the alarm shall be available for that purpose and that there be no undue waste of water.

It is the object of the present invention to 20 provide an apparatus which shall answer all the foregoing requirements, which shall be of simple construction and which shall contain no parts liable to get out of order or to become clogged as the result of any impurities 25 in the liquid.

These and other objects and features of the invention will appear more fully from the accompanying description and drawing and will be particularly pointed out in the claims.

The invention is disclosed as embodied in a liquid supplying system under pressure such as that employed in automatic fire sprinkler systems which control the flow of water to and through the sprinklers. As such systems are generally well known and familiar, and as the invention is concerned entirely with the apparatus for giving the alarm, it is only necessary here to illustrate and describe those features of such a system and apparatus 30 with which the invention is particularly concerned. Furthermore, as the alarm mechanism itself may be of any desired type or construction, and as such alarm mechanism forms no part of the present invention, it is unnecessary to illustrate and describe any such mechanism.

In an automatic fire sprinkler system, it is usually desirable that, whenever a sprinkler opens and therefore the water begins to flow 40 continuously through the sprinkler, the

alarm shall be given within half a minute after the continuous flow begins. It is also desirable that all the water diverted to operate the alarm shall be utilized for that purpose until the alarm is given, and that there 55 be no undue waste of water beyond what is necessary for this purpose. While water is wasted whenever the flow is sporadic due to changes in pressure, pulsations in the system, water hammer, etc., such waste is not large 60 and is practically unavoidable.

In the drawing:

Fig. 1 is a more or less diagrammatic view partially in vertical cross section of an apparatus embodying a preferred form of the 65 present invention.

Fig. 2 is a view chiefly in vertical cross section and on a larger scale showing the mouthpiece, nozzle and adjacent parts.

An alarm valve casing 1 is shown having 70 an inlet 2 normally connected with the supply of liquid under pressure, such, for example, as a city water system and having an outlet 3 normally connected to the sprinkler system from which the water is discharged, 75 when a fire occurs, through sprinklers in a familiar manner. This alarm valve casing is shown as provided with an alarm valve 4 pivoted at 5 and held by gravity and by the difference in pressures between the water 80 above and below the valve on the valve seat 6. At one side of the casing 1 a fitting 7 is inserted having an auxiliary valve seat 8 closed, when the valve 4 is seated, by an auxiliary valve 9, carried by an extension of the valve 4. A pipe 10 extends from the fitting 7 through a shut-off valve 11, through a suitable strainer 12 and through connections, to be described, to the retarding chamber 13. 85 From the top of the retarding chamber rises a pipe 14. This general arrangement is of a familiar type. The general idea is that whenever a continuous flow is started in the system, as by a sprinkler opening, the alarm valve 4 is swung open and a portion of the water flowing passes through the pipe 10, 90 fills the retarding chamber 13, passes up the pipe 14 and gives the alarm in any well-known manner. If, however, some pulsation 95 in the system occurs, as, for example, by a 100

sudden change in pressure of the main supply or otherwise, the alarm valve 4 may open partially and then drop back on its seat, thus allowing a sporadic flow of water through the pipe 10 into the retarding chamber. The retarding chamber is of such a size that such a flow will not fill the chamber, rise in the pipe 14 and give the alarm, and when the valve 4 returns to its seat, any water which has passed through the pipe 10 or entered the retarding chamber will be drawn off.

The present invention has to do mainly with the control of the flow of liquid into and out of the retarding chamber.

In the preferred construction illustrated, the retarding chamber a short distance above its base is provided with a preferably horizontally and radially extending mouthpiece 15 shown as threaded at 16 into a boss 17 formed in the wall of the chamber. This mouthpiece may be of any suitable form but preferably is designed on the principle of permitting a free flow of water from the retarding chamber when the valve 4 returns to its seat and after the water has passed the orifice. The throat, or that section of minimum area 18 at its inner end preferably enters the wall of the retarding chamber at 30 a right angle so as to present a sharp edge orifice 30. Otherwise, it is found in practice, the discharge flow from the retarding chamber might be too free. From the throat outward, that is, from the retarding chamber 35 the area of the mouthpiece enlarges gradually until it reaches its maximum area at about 19 which is the end of the mouthpiece proper. With such a mouthpiece, if smooth and well formed, the discharge of flow outwardly therethrough after passing the orifice 30 in 40 the wall of the retarding chamber will depend on the area of the mouthpiece at the section 19 and not on the area at the throat which therefore may be made quite small 45 without affecting the quantity of discharge. Such a mouthpiece is known as of the "divergent conoidal" type and liquid will under all conditions flow freely outwardly therethrough.

The pipe 10 terminates in a nozzle 20 located coaxially of the mouthpiece and having its discharge opening 21 adjacent the end of the mouthpiece proper and the area of the discharge opening 21 of the nozzle is made substantially equal to the area of the throat 18 and, if anything, slightly less in area.

The nozzle 20 is shown as threaded at 22 into an outwardly tapering extension 23 of the mouthpiece with a shouldered portion 24 abutting the end of this extension. The pipe 10 is conveniently threaded at 25 into the outer end of the nozzle.

It is desirable that, after the divergent conoidal mouthpiece has reached its maximum area at 19, that the area of flow through

the extension 23 shall not be diminished and as the nozzle 20 is necessarily of substantial thickness, the extension 23 is so shaped that the cross sectional area of the space 26 between the nozzle and the extension of the mouthpiece shall nowhere be less than the maximum area at 19.

A drain opening leading from the mouthpiece extension 23 is provided and is herein shown as including a pipe 27 threaded into a boss 28 at the bottom of the mouthpiece extension 23. The area of this drain opening is conveniently utilized to determine finally the outward flow from the retarding chamber. In the construction illustrated, the wall of the mouthpiece extension 23 above the boss 28 is drilled through to form a bore 29 of a diameter found to give the desired result. Under ordinary conditions it has been found that with the diameter of the bore 29 equal to the diameter of the nozzle opening 21, highly satisfactory results are achieved.

The parts are so correlated by being proportioned and arranged on the principle thus described that when the liquid flows continuously for a predetermined period under full head, as when a sprinkler opens, past the alarm valve 4 and consequently through the pipe 10, it will issue as a jet from the discharge opening 21 of the nozzle 20 and this jet will completely fill the throat 18 of the mouthpiece. Thus the liquid passes into the retarding chamber, fills the retarding chamber, and rises in the pipe 14 to operate the alarm with promptitude. Since the jet fills the throat 18, there can be no flow in a reverse direction out from the retarding chamber through the mouthpiece. Thus all the liquid diverted from the main through the nozzle is utilized to operate the alarm. No water flows out through the pipe 27 and in practice it is found that a substantial suction is formed at the drain opening. When the alarm is in operation, the resulting back pressure will, of course, result in some outward flow through the drain opening, which is unavoidable.

If, however, the flow through the pipe 10 is a sporadic one due to a slight opening or vibration of the alarm valve 4 and is very small, the liquid will run out through the nozzle 20, back through the space 26 and out the pipe 27. If larger, a part of the flow will pass from the nozzle 21, through the mouthpiece into the retarding chamber 13 and partially fill it. But immediately the valve 4 seats, the liquid in the retarding chamber flows rapidly out through the mouthpiece and its extension and thence through the pipe 27, so that the retarding chamber is quickly emptied.

It will be seen that the construction is of a simple form, that there are no movable parts and that there is nothing that can get out of order or become clogged or rendered

ineffective by reason of impurities in the liquid. When the liquid is discharging steadily from the nozzle 20, as when one or more sprinklers have opened, and consequently the liquid is under full head (the term "full head" meaning herein such a head as it is desired shall under the given conditions operate the alarm and which with a sprinkler system would be the head existing with one or more sprinklers open), the flow will be in the form of a jet at a high velocity due to the head in the system and the area of the discharge opening 21 is readily proportioned with respect to the throat 18 so that the jet will be of substantially constant area for the length of the mouthpiece and at the throat of an area equal thereto. Thus outward flow from the retarding chamber is prevented and all the liquid flowing is rendered available to fill the retarding chamber and operate the alarm.

While it is preferable that the construction be such as to cause the jet, when discharging steadily under full head from the nozzle 20, completely to fill the throat 18 and thus prevent any outward flow whatever, it is evident that substantial advantages may be secured with this invention even when the construction is such that the jet is somewhat smaller than the orifice so that some outward flow through the orifice around the jet may occur. But, in any event, the invention combines in a single orifice the admission and discharge opening to and from the retarding chamber and the invention thus presents a construction in which the jet controls the discharge from the chamber through the orifice or throat of the mouthpiece so that the required pressure may be built up in the chamber 49 within a predetermined time.

It will also be seen that any sporadic flow is quickly and freely drained off from the retarding chamber through the mouthpiece, its extension and the drain opening, while the flow of the discharge is readily controlled under the conditions by the area of the opening 29.

Thus repeated sporadic flows may take place without building up a sufficient pressure in the retarding chamber to operate the alarm unless conditions are reached equivalent to a continuous flow under full head for the predetermined period. The invention therefore, when applied to a sprinkler system, for example, insures the desired prompt and accurate operation of the alarm when a sprinkler opens and reduces the possibility of false alarms to the minimum.

Having thus described the invention, what is claimed as new, and desired to be secured by Letters Patent, is:

1. A retarding chamber for a liquid supplying system under pressure having a divergent connooidal mouthpiece, a nozzle connected to the supply system and located co-

axially of the mouthpiece with its discharge opening adjacent the greatest area of the mouthpiece and with the area of its discharge opening substantially equal to the area of the throat of the mouthpiece and a drain opening leading from the mouthpiece correlated to cause a continuous flow for a predetermined period through the nozzle under full head to produce a jet filling the throat of the mouthpiece thus filling the retarding chamber and preventing outward flow from the chamber and to cause sporadic flows through the nozzle to flow outward through the drain opening or partially to fill the retarding chamber and flow outward quickly and freely therefrom through the drain opening.

2. A retarding chamber having the construction defined in claim 1, in which the mouthpiece is provided with an extension outward surrounding the nozzle and presenting an area between itself and the nozzle not less than the maximum connooidal area of the mouthpiece, in which the drain opening extends from the area between the mouthpiece extension and the nozzle and in which the area of the drain opening determines the outward flow from the retarding chamber.

3. A retarding chamber having the construction defined in claim 1, in which the connooidal mouthpiece presents no abrupt change in area so that there is no abrupt change in velocity of liquid flowing outward therethrough from the retarding chamber.

4. A retarding chamber having the construction defined in claim 1 in which the end of the mouthpiece between the retarding chamber and the throat has the form approximately of a simple contracted vein and in which the mouthpiece from the throat outward enlarges gradually to an area unrestrictive of the quantity of discharge when liquid is flowing freely from the retarding chamber, and in which the discharge area from the end of the mouthpiece on out through the drain opening determines the outward flow from the retarding chamber.

5. A retarding chamber for a liquid supplying system under pressure in which the said chamber is closed except for an alarm-operating connection and for a single orifice acting both to admit liquid to, and discharge liquid from, the chamber, and a nozzle connected to the supply system located opposite said orifice and constructed and arranged to produce, when the flow through the nozzle is continuous for a predetermined period under full head, a jet filling the orifice, flowing into the chamber and preventing discharge from the chamber until the pressure required to operate the alarm is built up in the chamber by the liquid.

6. A retarding chamber for a liquid supplying system under pressure in which the said chamber is closed except for an alarm-oper-

ating connection and for a single mouthpiece through which liquid is both admitted to, and discharged from, the chamber, a drain opening leading from the mouthpiece, and a nozzle connected to the supply system and located coaxially of the mouthpiece and constructed and arranged to produce, when the flow through the nozzle is continuous for a predetermined period under full head, a jet filling the throat of the mouthpiece flowing through the mouthpiece into the chamber and preventing discharge from the chamber through the mouthpiece until the pressure required to operate the alarm is built up in the chamber by the liquid.

15 7. A retarding chamber for a liquid supplying system under pressure in which the said chamber is closed except for an alarm-operating connection and for a single orifice acting both to admit liquid to, and discharge liquid from, the chamber, and a nozzle connected to the supply system located opposite said orifice and constructed and arranged to produce, when the flow through the nozzle is continuous for a predetermined period under full head, a jet flowing through the orifice into the chamber and controlling the discharge from the chamber through the orifice to cause the pressure required to operate the alarm to be built up in the chamber by the liquid within a predetermined time.

20 8. A retarding chamber for a liquid supplying system under pressure in which the said chamber is closed except for an alarm-operating connection and for a single mouthpiece through which liquid is both admitted to, and discharged from, the chamber, a drain opening leading from the mouthpiece, and a nozzle connected to the supply system and located coaxially of the mouthpiece and constructed and arranged to produce, when the flow through the nozzle is continuous for a predetermined period under full head, a jet flowing through the throat of the mouthpiece into the chamber and controlling the discharge from the chamber through said throat to cause the pressure required to operate the alarm to be built up in the chamber within a predetermined time.

25 9. In testimony whereof, I have signed my name to this specification.
